[57] CLAIM

The ornamental design for a stackable chair, as shown and described.

DESCRIPTION

FIG. 1 is a perspective view of a stackable chair, this view being taken from above and from the left side; FIG. 2 is a right side view of the stackable chair; FIG. 3 is a front view of the stackable chair; FIG. 4 is a top view of the stackable chair; and, FIG. 5 is a rear view of the stackable chair. FIG. 2 through 5 have been shown on a reduced scale with respect to FIG. 1.

1 Claim, 3 Drawing Sheets

FIG. 1
